UNITED STATES PATENT OFFICE.

JOHN HENRY SCRUGGS, OF KNOXVILLE, TENNESSEE.

FOUNTAIN PUMP.

1,412,973.

Specification of Letters Patent. Patented Apr. 18, 1922.

Application filed October 4, 1920. Serial No. 414,587.

To all whom it may concern:

Be it known that I, JOHN HENRY SCRUGGS, a citizen of the United States, residing at Knoxville, in the county of Knox and State 5 of Tennessee, have invented a new and useful Improvement in Fountain Pumps, of which the following is a specification, reference being had to the accompanying drawing.

10 This invention relates to improvements in fountain pumps of the character now commonly employed in soda fountains, etc., and the object of the invention is to provide a pump of this character with a registering device which will show the proprietor of the 15 fountain just how many times the pump has been operated. In connection with this, I also employ a device for warning the attendant when the syrup is getting low, and also 20 a device which will prevent the pump from being operated a succession of small strokes in an effort to prevent the operation of the registering device.

The invention, in its preferable embodiment, consists in the arrangement and combination of parts hereinafter shown and described and then definitely claimed.

In the drawings accompanying and forming part hereof:

25 Figure 1 is a vertical central section of a fountain pump having my invention applied thereto.

Figure 2 is a sectional view through the line 2—2 of Figure 1.

30 Figure 3 is a section of the lower part of the pump showing the operation of a device for giving the attendant warning when the syrup is getting low.

Figure 4 is a detail.

35 Referring now to the details of the drawings by numerals: 1 designates a casing or receptacle which may be of any desirable form and which is usually supplied with a cover as that shown at 3. Within the casing or tank 1, is a pump which, generally speaking, may be of the ordinary form now in use and which consists of a pump cylinder 4 having the usual piston 6 working therein, the bottom of the cylinder being provided 40 with any form of suction valve 8 as shown in dotted lines in Figure 1. The piston has the usual stem 10 connected thereto which passes through a stuffing box 12 and has a handle 14 by which the stem 10 may be depressed and its piston 6 operated within

the cylinder 4, the stuffing box 12 having the usual spring, not shown, for returning the parts to the position shown in Figure 1. As in the usual embodiments of this device, a brace rod 16 is employed connecting the 45 pump cylinder 4 with the cover 3 by means of the horizontally offset member 18, this construction making it possible to remove at one time the cover and all the working parts from the casing or receptacle 1. The cylinder 4 is designed to rest on the bottom of the casing 1 and to that end is provided with feet as shown at 20. From the casing forming the cylinder 4 projects a vertically extended delivery pipe 22 whose upper end 50 connects with the nozzle 24 as shown in Figure 1. All the parts so far described may be of the ordinary construction and as my invention does not reside therein they may be altered at pleasure.

55 In order to protect the proprietor of the store, a registering device 25 is attached preferably to the interior of the cover 3 as indicated in Figure 1. Nothing new is claimed in this registering device per se as it may 60 be of a form well known on the market although I may add that in the present instance the cover 3 is provided with a sight opening 26 through which the numbers on the registering wheels may be viewed. From 65 the casing of the registering device projects a connecting rod 28 which is pivoted to a lever 30 pivotally supported by the brace rod 16. The free end of this lever 30 is slotted to accommodate a screw 32 which is 70 carried by a clamping collar 34 supported by the pumping stem 10. It follows from the construction shown and described that whenever the pumping stem 10 is depressed, the lever 30 will be moved downwardly upon 75 its pivot so as to force the connecting rod 28 upwardly to operate the registering device. The proprietor can tell from an examination of the register just how many 80 sales have been made in which the syrup 85 from this receptacle was used.

90 In order to make it impossible to move the pumping stem 10 downward part way for a succession of short strokes in an effort not to move it sufficiently to operate the register, 95 I use a supplemental device preferably consisting of the following elements. The pumping stem is provided with a collar 40 having a pawl 42 pivotally supported thereon. On some stationary part of the device, 100

110

as on the delivery tube 22, I provide a rack bar or series of teeth 43 adapted to be engaged by the pivoted pawl 42. I also provide two stops as those designated by the numerals 46 and 48 shown as projecting from the delivery tube 22. These stops are intended to co-act with the pivoted pawl 42 at each end of its stroke. A spring 50 is provided for the pivoted pawl 42 and the latter is provided with a cam as 44 which is designed to engage with the spring 50. When the cam 44 on said pawl is in one position, the pawl 42 will be held out of engagement with the teeth as shown in dotted lines in Figure 4, but when the cam is in the position shown in full lines in Figure 4, the pawl will be pressed by its spring 50 against the teeth 43. The operation of this part of the device is as follows: Assuming that when the pumping stem 10 moves upward to the position shown in Figure 1, the pawl 42 strikes the stop 46 and moves its cam 44 to the position shown in full lines in Figure 4, the spring 50 will press the pawl against the teeth 43 on the delivery tube 22. Therefore, if the attendant presses down even part way on the handle 14 of the pumping stem 10, the pivoted pawl, being in engagement with the ratchet wheel 44, will prevent the stem from moving or being moved upward. The only way the attendant can get the stem back to the normal position shown in Figure 1 is to move the stem all the way down to the extreme lower end of its stroke. When this is done the pivoted pawl 42 strikes against the stop 48 and the pawl is moved out of engagement with the teeth 43 and the spring 50 will hold the pawl out of engagement with said teeth. Now that the pawl is out of engagement with said teeth the pumping stem 10 can move to the upper end of its stroke. However, just as it reaches the upper end of the stroke, the pawl 42 will engage the stop 46 and move said pawl 42 until its cam is in the position to again engage the teeth 43 of the delivery tube 22. It will thus be seen that I have provided effective means for preventing the attendant from giving a succession of short movements to the pumping stem 10 and thus slowly pumping small quantities of syrup without operating the registering device, or of preventing the pump and pump rod from being raised until they complete the full downward stroke.

Another improvement I have illustrated is that shown in connection with the pump itself. In order to inform the operator when the syrup has been almost completely pumped from the casing 1, I provide the pump cylinder 4 with a pivoted lever 52. This lever is provided with a latch 54 which is held by means of a float 56 in the inactive position shown in Figure 1. Whenever the syrup becomes so slow that the float 56 will drop to the position shown in Figure 3, this

latch 54 moves into the position shown in Figure 3 and prevents the pump piston 6, its pumping stem 10 and the handle 14 from moving upward to the full extent of the stroke. This will warn the attendant of the low supply of the syrup. When the attendant places a new supply in the tank, he resets the lever 52 so that the float 56 will hold the parts in the position shown in Figure 2.

From the foregoing and accompanying drawings, it will be seen that I have invented a fountain pump in which a very simple form of registering device is employed and with this a safety device which will prevent the attendant from operating the pump without operating the register.

It will be obvious that changes and modifications may be made without departing from the spirit of my invention, the scope of which is set forth by the appended claims.

What I claim as my invention is:

1. In an apparatus of the kind described, the combination of a tank, a cover therefor, a member supported by and depending from said cover within the tank, a pump and pump rod, and a device located in the tank and co-acting with said depending member and said pump rod for preventing said rod from returning until it has completed its full forward stroke.

2. In an apparatus of the kind described, the combination of a tank, a cover therefor, a member supported by and depending from said cover within the tank, a pump and pump rod, and a device located in the tank and co-acting with said depending member and said pump rod for preventing said rod from returning until it has completed its full forward stroke, and a registering device operated by each stroke of said pump rod.

3. In an apparatus of the kind described, the combination of a tank, a cover therefor, a member supported by and depending from said cover within the tank, a pump and pump rod, and a device located in the tank and co-acting with said pump rod and member for preventing said pump rod from being given a succession of short strokes.

4. In an apparatus of the kind described, the combination of a tank, a cover therefor, a member supported by and depending from said cover within the tank, a pump and pump rod, a registering device operating by each stroke of said pump rod, and a device located in the tank and co-acting with said depending member and said pump rod for preventing said pump rod from being given a succession of short strokes to avoid operating said registering device.

5. In an apparatus of the kind described, the combination of a tank, a cover therefor, a member supported by and depending from said cover within the tank, a pump and pump rod, and a ratchet mechanism located in the tank and co-acting with said

- depending member and said pump rod for preventing said rod from returning until it has completed its full forward stroke.
6. In an apparatus of the kind described, the combination of a tank, a cover therefor, a member supported by and depending from said cover within the tank, a pump and pump rod, ratchet teeth on said depending member, a pawl carried by said pump rod in the tank and adapted to engage said teeth during the forward stroke of said pump rod to prevent said rod from being given a succession of short strokes, and means for moving said pawl into and out of engagement 15 with said teeth.
7. In an apparatus of the kind described, the combination of a tank, a cover therefor, a discharge pipe supported by and extending through said cover into said tank, a pump and pump rod, and a device located in the tank and co-acting with said discharge pipe and said pump rod for preventing said rod from returning until it has completed its full forward stroke.
- 25 8. In an apparatus of the kind described, the combination of a tank, a cover therefor, a discharge pipe supported by and extending through said cover into said tank, a pump and pump rod, and a device located in the tank and co-acting with said discharge pipe and said pump rod for preventing said rod from returning until it has completed its full forward stroke, and a registering device in operative relation with said pump 35 rod for registering during each stroke of said pump rod.
9. In an apparatus of the kind described, the combination of a tank, a cover therefor, a discharge pipe supported by and extending through said cover into the tank, a pump and pump rod, a ratchet mechanism located in the tank and co-acting with said discharge pipe and said pump rod for preventing said rod from returning until it has completed its full forward stroke.
- 40 10. In an apparatus of the kind described, the combination of a tank, a cover therefor, a pump cylinder and a pump rod, a rigid member extending from the lower face of the cover downward in the tank and rigidly joined to said cylinder, and a device located in the tank and co-acting with said rigid member and said pump rod for preventing said rod from returning until it has completed its full forward stroke.
- 45 11. In an apparatus of the kind described, the combination of a tank, a cover therefor, a pump cylinder and a pump rod, a rigid member extending from the lower face of the cover downward in the tank and rigidly joined to said cylinder, a ratchet mechanism located in the tank and co-acting with said rigid member and said pump rod for preventing said rod from returning until it has completed its full forward stroke.
- 50 12. In an apparatus of the kind described, the combination of a tank, a cover therefor, a pump cylinder and a pump rod, a discharge pipe supported by and extending downward from the cover in the tank and rigidly joined to said cylinder, and a device located in the tank and co-acting with said discharge pipe and said pump rod for preventing said rod from returning until it has completed its full forward stroke.
- 55 13. In a device of the character described, the combination of a tank, a pump near the bottom thereof, and a device co-acting with and through said pump for warning the attendant when the supply of liquid is low.
14. In a device of the character described, the combination of a tank, a pump near the bottom thereof, a piston for said pump, and a device operating to prevent said piston from completely operating when the liquid in the tank becomes low.
15. In a device of the character described, the combination of a tank, a pump near the bottom thereof, a piston for said pump, a device co-acting with and through said piston to warn the attendant when the supply of liquid becomes low, and a float to control the operation of said device.
16. In a device of the character described, the combination of a tank, a pump near the bottom thereof, a piston for said pump, a latch co-acting with said piston to lock the same and warn the attendant that the supply of liquid is low, and a float to control the operation of said latch.
17. In a device of the character described, the combination of a tank, a pump near the bottom thereof, a piston for said pump, a latch pivoted to the cylinder casing and adapted to project into the path of said piston to lock the same and warn the attendant that the supply of liquid is low, and a float to control the operation of said latch.
- In testimony whereof I have signed my name, in presence of two witnesses, this first day of October, in the year one thousand nine hundred and twenty.
